Patented May 11, 1926.

UNITED STATES PATENT OFFICE.

FRED J. POSTEL, OF CHICAGO, ILLINOIS.

NONSCALDING WATER HEATER.

Application filed July 30, 1923. Serial No. 654,585.

My invention relates to heat interchanging appliances in which the exchange of heat is effected through an intermediary and normally liquid medium, and particularly to appliances designed for heating liquids.

Viewed in some of its many aspects, my invention provides a heat-interchanging appliance of this general class which will automatically limit the degree to which heat is transmitted to the heat-receiving member of the appliance; which will accomplish this limitation primarily by converting an intermediary and normally liquid heat-transmitting medium into a vapor to such an extent as to reduce the heat transmission through this medium; which will afford a ready storage for liquid forced out of the heat-interchanging portion of the appliance by the generation of such vapor; which will automatically return such expelled liquid to the main portion of the appliance when the excessive heating ceases; which will avoid any material loss of the vaporizable liquid medium; and which will be effective for limiting the temperature of the heat-receiving portion of the appliance to a temperature close to that at which the intermediary or heat-transmitting liquid readily vaporizes.

Furthermore, my invention provides for the use of an auxiliary heat-carrying liquid in conjunction with a more readily vaporizable liquid upon whose vaporizing temperature the control of the heat interchange depends, and provides an apparatus which will readily permit a relatively expensive vaporizable liquid to be used in conjunction with a much larger quantity of a cheap secondary liquid; provides means whereby the heat is supplied to the said vaporizable liquid more speedily and to a greater extent than to the secondary liquid; provides means whereby the pressure due to a vaporization of the more easily vaporizable liquid will primarily expel part of the secondary liquid; and provides an apparatus in which the heating of the secondary liquid will cooperate with the more intense heating of the vaporizable liquid in affording a speedy interchange of heat between the heat-supplying and the heat-receiving portions of the apparatus and in effecting a sensitive control of the temperature of the said heat-receiving portion.

My invention also provides a heat-transferring medium consisting of a plurality of liquids one of which will readily vaporize

long before the heat-transferring medium as a whole approaches the boiling point of the said vaporizing liquid, provides a two-liquid medium for this purpose in which the vaporizing liquid desirably is not miscible with the secondary liquid but is of such higher specific gravity as to cause the said secondary liquid to float on the vaporizing liquid, and provides for the ready use of an easily obtained and vaporizing liquid of highly desirable characteristics in combination with water as a heat-transferring medium for a non-scalding water heater.

Still further and also more detailed objects of my invention will appear from the following specification and from the accompanying drawings, in which

Fig. 1 is an elevation of a non-scalding water heater embodying my invention, with a portion of the container wall broken away to show the disposition of the steam and water ducts within the same.

Fig. 2 is a simplified diagrammatic view showing the disposition of the liquids in a temperature-limiting hot water heater when the apparatus is cold.

Fig. 3 is a similar diagram showing the disposition of the liquids when the apparatus is having its temperature limiting effect.

Referring first to the diagram of Fig. 2, this shows a container 1 having a water supply duct 2 extending upwardly through the same and also having a steam supply duct 90 disposed within it. This steam supply duct comprises an inlet section 3 which enters the container at a distance above the bottom of the latter and which then extends downwardly and opens through a T connection 14 into a vertical steam pipe 4 which has its main portion extending upwardly to a point somewhat below the top of the container and then continued by a downwardly extending section 5 of greater surface. Both the said section 5 and the lower portion of the riser pipe 4 are connected outside of the container to a return pipe 6 through which any condensate from the steam is discharged.

The lower portion of the container is filled to a height approximating that of the inlet portion of the steam pipe 3 by a heavy liquid 7 which is readily vaporizable at a temperature below that to which the water is to be heated. For this purpose I desirably employ carbon tetrachloride which, although it only boils at a temperature of ap-

proximately 170° F. will vaporize rapidly at a temperature of about 120°. Floating on this vaporizing liquid is a relatively greater volume of water 8 which extends substantially to the top of a container.

When steam is admitted through the inlet pipe 3, the inlet section of this pipe, being immersed in the carbon tetrachloride, heats the latter intensely and almost instantly

- 10 causes it to boil, thereby producing vapor which rises into the water above it, where it is condensed (if the water 8 is cold) and again falls to the bottom. Initially, the supplied steam may all be condensed in the 15 downwardly extending inlet section, but later the steam not condensed in that section passes up the riser 4 and the main section 5 of the steam pipe and also heats both the carbon tetrachloride and the water, so that 20 both liquids then act as a medium for conveying heat to the heat-receiving water duct 2. Any steam condensed in the steam pipe sections flows downward into the return pipe 6, the customary steam traps in the pipe system being omitted in the diagrams to 25 simplify the latter.

When the water 8 in the container reaches a temperature of about 120°, this water no longer condenses the vapor of the carbon tetrachloride but rather tends to superheat the vapor and hastens the vaporizing, so that this vapor accumulates rapidly in the top of the container or above the top of the water 8, where it creates a pressure above the water. To utilize this pressure, I provide 30 a storage tank 9 disposed above the normal level of the water and having its bottom connected to the container by a pipe 10 which desirably leads into the container at 35 a point above the normal level of the carbon tetrachloride. This storage tank has at its top an air vent 10' but is empty when the apparatus is cold. As soon as pressure is 40 produced above the water by the accumulation of vapor from the volatile liquid, this pressure forces water up the pipe 10 and into the storage tank 9, thereby gradually 45 storing water in this tank as shown in Fig. 3 and correspondingly lowering the level of 50 the water in the container as shown in the same figure.

As long as both the heat-supplying duct (here comprising steam pipe portions 3, 4 and 5) and the heat-receiving duct (namely the water pipe 2) are immersed in the heat transferring medium consisting of the two liquids, these liquids afford a ready conduction of heat from one to the other. However, as the level of the upper liquid falls, portions of both of these ducts are exposed to an increasing extent above the same and since any vapor is a much poorer conductor of heat than a liquid, the rate of the heat-transferring is considerably decreased. Consequently, the effective temperature at-

tained in the water supply pipe remains below the temperature to which the heat-transferring liquids are warmed, so that the temperature of the liquid in the heat-receiving duct is automatically limited. By varying the height of the storage tank with respect to the container, (as shown for example in dotted lines in Fig. 1) and hence altering the pressure of the liquid in the pipe 10, I can vary the pressure against which vapor 75 expels liquid into the storage tank and hence can adjust the limiting action of my apparatus to some extent so as to adapt the same to temperature not corresponding exactly to the vaporizing-point of the more vaporizable liquid.

In practice, I may not depend entirely on this automatic regulating feature of my apparatus, but may also employ an automatically operating steam control valve so 85 as to reduce the blowing of the liquid into the storage tank where some of it will gradually be evaporated and wasted. For example, Fig. 1 shows the steam inlet pipe 3 as controlled by a valve 11 operated from a thermostat 12 disposed in the upper portion of the container 1, the steam inlet pipe entering the container somewhat above the top of the carbon tetrachloride 7 and the connection of the discharge pipe 10 to the 95 container. The inlet pipe 3 is connected at its lower end through a T 14 to a steam riser pipe 4 which is connected at its upper end to the top of a coiled steam pipe section 5, and the lower end of this coil is connected through an outlet pipe 15 and a steam trap 16 to a suitable drain pipe. Likewise, the T 14 is connected through a drain pipe 17 and a trap 18 to a drain pipe.

The water which is to be heated enters the 105 container through the inlet pipe 19 and then passes through pipes 20 extending vertically through the container proper, which container forms the central section for a water tank having an upper outlet 21 for the 110 heated water. To store the water forced out through the discharge pipe 10 by the pressure of the vapor, I connect this pipe 10 to the bottom of a storage tank 9 having an air 115 vent 22 similar to that mentioned in connection with the diagrams of Figs. 2 and 3.

When a thermostatic valve 11 is thus employed and is in proper operative condition, this valve will control the supply of steam automatically so as to maintain approximately the desired temperature in the heated water without requiring my safety feature to operate. However, if this valve should fail to operate, the formation of vapor causes liquid to be forced into the storage tank 9 whereupon the reduction in the heat transfer due to the formation of this vapor automatically limits the temperature of the water, thereby acting as a positive safeguard for limiting the temperature to which the 130

water is heated. In practice, I desirably provide a gage glass 23 from which the level of the liquids can be seen at a glance, and I have found that if the thermostatic valve is 5 blocked wide open while no water is being withdrawn from the outlet 21 of the tank, the level of the upper liquid falls rapidly while the temperature of the heated water in the tank remains practically constant. 10 Hence my simple arrangement affords an entirely automatic control and by selecting a vaporizable liquid of a suitable rapid-vaporizing temperature, I can readily secure the desired temperature limitation in the 15 heat-receiving liquid. Where the latter is water, as employed in hospitals, asylums or the like for administering baths, carbon tetrachloride is highly suitable as a vaporizable liquid, since it permits a relatively 20 large quantity of water to float on it and readily limits the temperature of the heated water to about 120° F.

Since the vapor occupies a much greater 25 space than the unvaporized liquid, a relatively small quantity of the carbon tetrachloride is ample for the purpose, but I desirably employ a somewhat greater quantity so as to have more of the hot steam 30 pipe section immersed in it, as for example about one part of carbon tetrachloride to 25 parts by volume of water. In practice, a little of the vaporized carbon tetrachloride may be expelled with the water into the storage tank, but as the latter is cooled by 35 the outer air and only has a small air vent, any vapor forced into it is readily condensed and flows back into the container. Hence 40 my two-liquid arrangement not only permits the use of a relatively small quantity of the vaporizable liquid but also prevents any substantial waste of the same. Furthermore, 45 since the temperature limiting feature of my apparatus involves no moving mechanism, it requires no attention of any kind and has nothing about it to get out of order.

By using non-miscible liquids in the above manner, I can limit the expulsion of liquid 50 into the tank almost wholly to the lighter liquid, thereby reducing even the gradual evaporation within the tank of the heavier liquid which, as in the case of carbon tetrachloride is much more expensive, and I can 55 also secure greater sensitiveness than with liquids which are miscible. However, I may employ two miscible liquids of different vaporizing points and hence do not wish to be limited in this respect. Neither do I wish 60 to be limited to using liquids one of which readily vaporizes at substantially the desired limiting temperature, as the effective 65 limiting temperature attained with my invention can be varied by raising or lowering the storage tank so as to decrease or increase the readiness with which the generated vapor forces liquid into the tank.

So also, while I have described my invention as employed for water heating purposes, I do not wish to be limited to this use of the same nor to the use of the vaporizable liquid which I have found particularly advantageous in hydrotherapeutic installations. Neither do I wish to be limited to the above described construction and arrangement of a suitable heat-transferring apparatus, it being obvious that the same 70 might be varied in many ways without departing either from the spirit of my invention or from the appended claims.

I claim as my invention:—

1. A heat interchange appliance comprising 80 a closed container, a heat supplying duct and a heat receiving duct both extending through the container; a heat transferring medium within the container comprising two non-miscible liquids of different specific gravities and vaporizing points, and a storage tank connected to the container within the zone of the less volatile liquid.

2. A heat interchange appliance comprising 85 a closed container, a heat supplying duct and a heat receiving duct both extending through the container; a heat transferring medium within the container comprising two non-miscible liquids of different specific gravities and vaporizing points, a storage tank disposed higher than the normal top of the said medium, and a connection leading from the bottom of the tank to the container and connected to the latter within 90 the zone of the less volatile liquid, the storage tank having a vent open to the outer air.

3. A heat interchange appliance for heating 95 a fluid to a substantially predetermined limiting temperature only, comprising a closed container, a heat supplying duct disposed within the container and connected to a supply of heating fluid at a temperature in excess of the said limiting temperature, a heat receiving duct connected to the fluid which is to be heated and also disposed within the container, a heat transferring medium within the container comprising two non-miscible liquids of different specific gravities and vaporizing points, the 105 quantity of the liquid having the lower vaporizing point being such that its vapor will more than fill the container, the two liquids together being of such a volume as normally to fill at least the greater part of the container, an expansion tank disposed higher than the container, and a duct connecting the bottom of the tank with the container at a point normally opposite the liquid having the higher vaporizing point. 110

4. In a heat interchange appliance, a closed container, a heat transferring medium partly filling the container and comprising a relatively heavy liquid and a 115 lighter liquid normally floating on the said 120

- heavy liquid, the heavier liquid having a lower vaporizing point than the lighter liquid, a heat transmitting duct extending through both liquids and through the space above the lighter liquid, a heat transmitting duct extending initially into the heavier liquid and thereafter into the lighter liquid, and a vented tank connected to the container above the heavier liquid and below the normal level of the lighter liquid.
5. A heat interchange appliance comprising a closed container, a heat supplying duct and a heat receiving duct both disposed within the container; and a liquid mixture within the container comprising a layer of a liquid heavier than water and of lower vaporizing temperature than water, and a larger amount of water normally floating upon the said layer, the heat supplying duct having a downwardly directed entrance portion disposed below the normal top of the heavier liquid, and a continuation portion connected to the bottom of the said entrance portion and extending through both liquids into the space above them, and a trap connected to the connection between the said two duct portions.
6. A non-scalding hot water heater comprising a closed container, a steam pipe and a water pipe both extending through the container, a liquid heat-transferring medium partly filling the container and comprising water and a second liquid not miscible with water and of distinctly different specific gravity and lower boiling point than water, and a vent duct connected to the container within the zone of the water and extending upwardly from its said connection.
7. A water heater as per claim 6, in which the steam pipe has its hottest portion disposed in the said second liquid and in which a relatively cooler portion of the steam pipe as well as a part of the water pipe extend into the space above the said medium.
8. A water heater as per claim 6, in which the normal quantity of water is considerably greater than that of the said second liquid.
9. A non-scalding hot water heater comprising a closed container, a steam duct and a water duct both extending through the container, and a liquid medium partly filling the container, the said medium comprising carbon tetrachloride and water, both the steam pipe and the water pipe hav-
- ing portions disposed above the level of the liquid medium when the heater is in operation, and a vent duct connected to the container within the zone of the water and extending upwardly from its said connection.
10. A non-scalding hot water heater comprising a closed container, a liquid medium partly filling the container, the said medium comprising carbon tetrachloride and a relatively greater quantity of water, a steam duct and a water duct extending through the container and through both of the said liquids; a vented and normally empty storage tank; and a pipe leading from the bottom of the storage tank and connected to the container above and adjacent to the normal level of the carbon tetrachloride.
11. A temperature-limiting heat interchange appliance comprising a closed container, a heat transfer medium partly filling the container and comprising two non-miscible liquids, namely a liquid having a vaporizing point somewhat above the desired limiting temperature afforded by the appliance, and a second liquid of lower specific gravity and relatively higher vaporizing point; a heat-transmitting duct and a heat-receiving duct both extending through the container and through both liquids and having portions of both ducts disposed in the space between the top of the container and the top of the lighter liquid; and a venting duct connected to the container within the zone of the lighter liquid and near the normal top of the heavier liquid and extending upwardly from its said connection.
12. A non-scalding hot water heater comprising a closed container, a layer of carbon tetrachloride in the container, a relatively larger volume of water floating thereon and having its normal top spaced from the top of the container; a heating duct and a water duct both extending through both of the said liquids and into the space above the water, the heating duct being disposed for heating the carbon tetrachloride more intensely than the water; and a venting duct connected to the container within the zone of the water and normally slightly above the top of the carbon tetrachloride.

Signed at Chicago, Illinois, July 27th, 1923.

FRED J. POSTEL.
